UNITED STATES PATENT OFFICE.

ROSE E. PARROTT, OF McCALLSBURG, IOWA.

BUTTER CUTTER.

Application filed September 7, 1921. Serial No. 499,003.

To all whom it may concern:

Be it known that I, ROSE E. PARROTT, a citizen of the United States, and a resident of McCallsburg, in the county of Story and State of Iowa, have invented a certain new and useful Butter Cutter, of which the following is a specification.

The object of my invention is to provide a device of simple, durable and inexpensive construction adapted to receive a brick of butter, and provided with means whereby the said brick of butter may be cut into small sections such as are commonly used on individual butter plates in restaurants.

More specifically, it is the object of my invention to provide a container for receiving the brick of butter, the said container being provided with guide slots so arranged that suitable cutters may be inserted for cutting the brick into small sections by comparatively a few number of operations, the container being so arranged that the small sections of butter may be removed as wanted for use.

These and other objects will be apparent to those skilled in the art.

My invention consists in the construction, arrangement and combination of the various parts of the device, whereby the objects contemplated are attained, as herein-after more fully set forth, pointed out in my claims, and illustrated in the accompanying drawings, in which:

Figure 1 is a perspective view of my improved container with one corner broken away to show the manner in which the small cakes of butter are arranged within the container after they have been cut.

Figure 2 is an inverted view of the container showing the manner in which the cutting devices are used in connection therewith.

Figure 3 is a perspective view of one of the cutters.

Figure 4 is a detail perspective view of a section of the cutters shown in Figure 2.

My improved apparatus comprises a rectangular container or box 10 which is of such a size that a pound cake or brick of butter may be easily placed therein, the bricks being of the size and shape as ordinarily produced by the creameries.

The container 10 is provided with a bottom 11, end members 12 and side members 13. One of the side members 13 is provided at its upper edge with a hinged cover 14.

The said cover is provided at its free edge with a downwardly extending flange 15, and its ends provided with downwardly and curved flanges 16, the flange 15 being designed to extend over the upper edge of the opposite side member from which the cover is hinged, and the flanges 16 designed to extend over the outside of the end members 12 when the cover is in its closed position.

The flange 15 is provided with a pivoted fastener plate 17 having an opening 18. This opening 18 is designed to receive a lug 19 which is secured to the outside of the front side member 13. This lug is provided with an opening 20 which is designed to receive a hook portion 21 of the pivoted member 22. This provides means whereby the cover may be secured in its closed position when so desired.

The bottom of the container 11 is provided with a series of parallel and transversely arranged slots 23, which are spaced apart a distance equal to the thickness of the small cakes of butter which is to be formed, and of a length equal to the width of the container 19, as clearly shown in Figure 2.

The cover member 14 is provided with a longitudinal slot 24 placed midway between the hinged portion and the flange 15, and of a length equal to said cover. The front side member 13 is also provided with a slot 25 midway between the top and bottom edge of said member, and of a length equal to its 90 length.

For cutting the brick of butter longitudinally, I have provided a cutter 26, clearly shown in Figure 3. This cutter comprises substantially a rectangular blade having a sharp cutting edge 27, and a handle supporting member 28 at its opposite edge, said member being designed to receive a handle 29, the said handle 29 being of such length and diameter that may be easily grasped in the palm of the operator's hand with the member 28 between the second and third fingers.

After the brick of butter has been placed in the container and the cover 14 closed and locked in position, the cutting edge 27 of the blade 26 may be placed in the slot 24 and forced downwardly until the cutter edge 27 strikes the bottom of the container. The container may then be rotated until it rests on its back side. This will leave the slot 25 in an uppermost position. The blade

26 may then be forced through the slot 25 and a longitudinal cut made through the brick at right angles to the first longitudinal cut. The blade 26 should always be 5 dipped in cold water between each operation.

For making the transverse cuts, I have provided a tool comprising a base member 30, having flange reinforcing members 31 at 10 each edge, and of a length equal to the length of the container 10.

This base member 30 is provided with a series of parallel and laterally extending plates 32, some of which are clearly shown 15 in Figure 4. These plates are spaced apart a distance equal to the spacing of the slots 23, the width of the plates being substantially equal to the length of said slot, and the depth of the cutters being slightly greater 20 than the depth of the container 10 and having their lower edge sharpened.

A bracket 33 is provided which is attached to a handle 34. The container 10 is placed in an inverted position with the bottom 11 25 uppermost, after which the cutting edges of the plates 32 are inserted in the slots 23, as clearly shown in Figure 2, and the handle 34 is then pushed downwardly, which will cause the brick of butter to be cut in a series 30 of transverse cakes. The cutter 30 may then be removed and the container turned to its upright position, after which the fastener 18 may be released and the cover 14 moved to an opened position. The brick of butter will 35 then be formed into a series of transverse cakes, each of which is divided into four other cakes, caused by the longitudinal cuts, as clearly shown in Figure 1. Any number 40 of these cakes may then be removed as wanted, or the container may be inverted and the whole number of cakes emptied on a table or any suitable receptacle. The cutter 30 should also be dipped in water before it is placed in the operative position.

45 By this arrangement, it will be seen that I have provided a container in which may be placed a pound of butter or similar article, after which it may be cut into a series 50 of small cakes by the use of the cutters 26 and 30, after which any number of cakes may be removed as used and the remaining cakes may be left within the container, if it is so desired.

One advantage of my device lies in the fact that the container is of such a size that 55 it will just receive a brick of butter. When the cutters are operated, the sides of said container will serve to retain the rectangular outline of the small cakes, which will be of uniform shape and size. This also provides 60 means whereby the number of cakes of butter obtained from the single brick may be predetermined.

Another advantage of my apparatus lies in the fact that a brick of butter may be 65 cut into a number of small cakes by comparatively a few number of operations, and when so cut will be accurate in size and shape.

I claim as my invention:

70 1. A rectangular container having one side adapted to be opened so that a brick of butter may be placed in said container, the bottom of said container being provided with a series of parallel and transversely arranged 75 slots, and one of said sides being provided with a longitudinally arranged slot, substantially as described and for the purposes stated.

2. A container having a bottom, side and 80 end members, a cover member, said bottom member being provided with equally spaced and parallel slots, one of said side members and said cover member being provided with a longitudinal slot.

85 3. A rectangular container having a bottom, parallel sides and parallel ends and a hinged cover, the said bottom being provided with a series of equally spaced parallel and transversely arranged slots, one 90 of the said side members being provided with a central and longitudinal slot, said top member also being provided with a central and longitudinal slot, and means for fastening said cover in a closed position.

95 4. A container having a bottom, side and end members, a cover member, said bottom member being provided with equally spaced and parallel slots, extended to points slightly spaced from the side members, one 100 of said side members and said cover member being provided with a longitudinal slot extended to points slightly spaced from the end member.

Des Moines, Iowa, May 20, 1921.

ROSE E. PARROTT.
